UNITED STATES PATENT OFFICE.

JUAN ANTIGA Y ESCOBAR, OF HABANA, CUBA.

DESIGN FOR A PUZZLE OR GAME BOARD.

30,450.

Specification for Design.

Patented Feb. 21, 1922.

Application filed September 10, 1920. Serial No. 409,484. Term of patent $8\frac{1}{2}$ years.

To all whom it may concern:

Be it known that I, JUAN ANTIGA Y ESCOBAR, a citizen of the Republic of Cuba, residing at Habana, Cuba, have invented a new, original, and ornamental Design for Improvements in Puzzle or Game Boards, of which the following is a specification, reference being had to the accompanying drawing, forming part thereof.

Figure 1 is a plan view of the puzzle.

Figure 2 is a vertical section through the same.

I claim:

The ornamental design for a puzzle or game board, as shown.

JUAN ANTIGA Y ESCOBAR.
